UNITED STATES PATENT OFFICE

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS

FASTENER FOR CURTAIN ROD ORNAMENTS

Application filed May 20, 1931. Serial No. 538,682.

This invention relates to an improved fastener for removably attaching an ornament to a curtain rod. The invention has been designed more especially for attaching ornaments to rods of the flat type, but is capable of use with rods of other cross-sectional forms.

Curtain rod ornaments are usually made as metal castings, and, as such, are of considerable weight. Where such an ornament is attached to the rod by a spring clip embracing the upper and lower rounded edges of the rod, the friction between the clip and the rod is insufficient to hold the ornament in a true vertical position, and the result is that the ornament sags more or less and thus presents an unsightly appearance.

The primary object of the present invention has been to provide an improved means for detachably securing an ornament to a curtain rod which would obviate the above noted fault, and would maintain the ornament in a true vertical position. Another object has been to provide an improved fastener of the spring clip type that could be applied to, and would function satisfactorily on, rods of slightly different transverse dimensions, such, for instance, as the outer rod and the inner rod of an ordinary telescoping extensible rod.

The present invention in its preferred form provides on the rear side of the ornament a pair of spaced lugs adapted to have an extended bearing on and crosswise of the flat front face of the rod, and, in association therewith, a generally C-shaped spring fastening clip attached to the rear wall of the ornament between said lugs, the arms of the clip straddling the upper and lower edges of the rod, preferably with clearance, and bearing upon the rear wall of the rod and of such reach as to press the front wall of the rod hard against the bearing surface of the lugs, whereby any tendency of the ornament to dip or turn on the rod under its weight is effectively overcome.

The invention, its manner of use, and the advantages inherent therein will be readily apparent to persons skilled in the art from the following detail description, taken in connection with the accompanying drawings, in

which I have illustrated practical embodiments of the invention, which, in practice, have been found to satisfactorily effectuate the stated purposes and objects thereof, and in which—

Fig. 1 is a front elevation of a fragment of a flat curtain rod showing a center ornament applied thereto.

Fig. 2 is a rear elevation of Fig. 1, showing the fastening clip.

Fig. 3 is a vertical transverse section taken on the line 3—3 of Fig. 2.

Fig. 4 is a view similar to Fig. 3, illustrating a slight modification in the bearing lugs on the rear of the ornament.

Fig. 5 is a plan section taken on the line 5—5 of Fig. 2.

Fig. 6 is a side view of the fastening clip.

Referring to the drawings, 10 designates a fragment of an ordinary hollow flat curtain rod, and 11 designates as an entirety a center ornament in the form of a metal casting. As best shown in Figs. 3 and 5, on the rear side of the ornament 11 are formed, preferably in the casting operation, a pair of rod abutment members in the form of spaced parallel lugs or ribs 12 formed with flat free edges. Midway between the lugs 12 is a tapped hole 13 in the ornament casting adapted to receive a screw 14 by which a generally C-shaped spring clip 15 is secured at its intermediate portion to the rear side of the casting between the lugs 12. To prevent any danger of cracking or breaking the clip at its center, and insure a broad contact of the central portion of the clip with the wall of the casting, I preferably form such central portion flat, as shown in Fig. 6, and also preferably interpose a substantial metal washer 16 beneath the head of the screw 14.

As will be seen by inspection of Fig. 3, the projecting arms of the spring clip 15 span the upper and lower edges of the rod 10 and to a limited extent overhang the rear wall of the rod, bearing upon the latter at the points indicated by α . The pressure of the spring arms at these points on the rear wall of the rod forces the flat front wall of the rod hard against the flat bearing surfaces of the abutment lugs 12, so that, as a result of this double

point contact at the rear and line contact at the front, the ornament is effectively locked against a tendency to turn by gravity on the rod, and the ornament is thus maintained 5 in true upright position.

It will also be observed that the thickness of the clip 15, washer 16, and head of the screw 14 is less than the height of the bearing lugs 12, so that the means for attaching the 10 clip to the ornament do not at all interfere with the pressing of the rod against the lugs by the spring fingers of the clip.

In Fig. 4 I illustrate a slight modification, wherein, instead of employing a single continuous lug 12 on each side of the clip, I may employ a pair of spaced lugs 12' on each side of the clip, each lug 12' having a bearing surface for the front wall of the rod.

By reason of the described construction, it 20 is entirely practicable to make the spring arms of the clip 15 sufficiently long to function satisfactorily with either the inner section or the outer section of a sectional telescopic rod.

25 The ornament is preferably applied to the rod before the latter is mounted on its supporting brackets, and in making such application the upper rounded edge of the rod is preferably slipped beneath the upper arm 30 of the clip, and the lower rounded edge of the rod is then sprung inwardly over the lower arm of the clip. As soon as the rod is fully entered, as shown in Fig. 3, the arms spring inwardly and engage with the rear 35 wall of the rod at the points *a*, as above explained, thus causing the front wall of the rod to set firmly on and across the lugs 12.

If, however, the rod has already been 40 mounted, the ornament may be applied to the rod by first tilting the ornament and passing one of the arms 15 over one edge of the rod, and then springing the other arm 15 over the other edge of the rod, which brings the ornament to the true vertical position.

45 I claim:

1. In combination with a curtain rod ornament with spaced lugs on its rear side, a fastening clip attached to the rear side of said ornament between said lugs, said clip 50 formed with spring arms adapted to straddle a curtain rod and of such form and reach as to press the face of the rod against said lugs.

55 2. In combination with a curtain rod ornament with spaced lugs on its rear side, a generally C-shaped spring fastening clip having its central portion attached to the rear side of said ornament between said lugs, the arms of said clip adapted to straddle a curtain rod and bear on the rearwall of the latter and of such reach as to press the face of the rod against said lugs.

60 3. In combination with a curtain rod ornament with spaced lugs on its rear side, a 65 generally C-shaped spring fastening clip of

less thickness than the height of said lugs attached to the rear side of said ornament between said lugs, the arms of said clip adapted to span the top and bottom edges of a flat curtain rod with clearance and bear on the 70 rear wall of said rod and of such reach as to press the face of the rod against said lugs.

4. In combination with a curtain rod ornament having on its rear side spaced parallel lugs having flat free edges adapted to have a 75 continuous bearing on and crosswise of a flat curtain rod, a generally C-shaped spring fastening clip of less thickness than the height of said lugs attached to the rear side of said ornament between said lugs, the arms of said clip adapted to span the top and bottom edges of a flat curtain rod with clearance and bear on the rear wall of said rod and of such 80 reach as to press the face of the rod against the flat free edges of said lugs.

5. In combination with a curtain rod ornament having on its rear side spaced lugs and with a hole between said lugs, a generally C-shaped spring fastening clip having 85 its central portion apertured and seated between said lugs, a washer overlying said central portion, and a fastening member passed through said washer and central portion and into said hole; the combined thickness of said washer and central portion of the clip 90 being less than the height of said lugs, and the arms of said clip adapted to span the top and bottom edges of a flat curtain rod with clearance and bear on the rear wall of said rod and of such reach as to press the face of the rod against 95 said lugs.

6. The combination with a curtain rod having a flat front face, of a curtain rod ornament formed with a flat abutment member on its rear side, and a fastening clip formed with 100 an intermediate portion attached to the rear side of said ornament adjacent to said abutment member and with spring arms adapted to straddle said rod and bear on the rear wall thereof, said arms having a reach such 105 as to press said rod against said abutment member.

7. The combination with a curtain rod having a flat front face, of a curtain rod ornament having spaced lugs on its rear side, and a fastening clip formed with an intermediate portion attached to the rear side of said ornament between said lugs and with 110 spring arms adapted to span the upper and lower edges of said rod and bear on the rear wall thereof, said arms having a reach such 115 as to press said rod against said lugs.

JAMES H. BOYE.
